(57) **CLAIM**

The ornamental design for an eyewear retainer, as shown and described.

DESCRIPTION

FIG. 1 is a front perspective view of an eyewear retainer, showing my new design;

FIG. 2 is a rear perspective view thereof;

FIG. 3 is a front elevation view thereof;

FIG. 4 is a rear elevation view thereof;

FIG. 5 is a top plan view thereof; and,

FIG. 6 is a bottom plan view thereof.

The broken lines in the figures are for the purposes of illustrating portions of the eyewear retainer, which form no part of the claimed design.

The article is shown with a symbolic break in its length. The appearance of any portion of the article between the break lines forms no part of the claimed design.
